UNITED STATES PATENT OFFICE.

ROBERT SANFORD RILEY, OF WORCESTER, MASSACHUSETTS, ASSIGNOR TO SANFORD RILEY STOKER COMPANY, OF WORCESTER, MASSACHUSETTS, A CORPORATION OF MASSACHUSETTS.

STOKER-DRIVING MECHANISM.

Application filed April 22, 1922. Serial No. 556,013.

To all whom it may concern:

Be it known that I, ROBERT SANFORD RILEY, a citizen of the United States, residing at Worcester, in the county of Worcester and State of Massachusetts, have invented a new and useful Stoker-Driving Mechanism, of which the following is a specification.

This invention relates to a mechanical stoker, and more particularly to an improved arrangement and disposition of driving mechanism for the different parts thereof. Such stokers necessarily include mechanically actuated fuel feeding means and provision for supplying air under pressure.

It is the object of my invention to provide a construction and assembly of these necessary parts, particularly adapted for a single unit stoker, and in which both the fuel feeding mechanism and the air supplying means may be conveniently driven from a single source of power.

More specifically, in the preferred form I provide a turbine or other prime mover to drive a fan for supplying the air under pressure and I provide a speed reducing connection between the turbine and the fuel feeding mechanism through which the latter may be driven at a reduced speed.

A further feature of my invention relates to the provision of an air opening and fan in the front wall of the furnace adjacent the fuel feeding mechanism and conveniently positioned for a combination drive therewith.

My invention further relates to arrangements and combinations of parts which will be hereinafter described and more particularly pointed out in the appended claim.

One form of my invention is shown in the drawings, in which—

Fig. 1 is a front elevation, partially diagrammatic, of an underfeed stoker embodying my improvement;

Fig. 2 is a longitudinal sectional elevation thereof, partially diagrammatic, taken along the line 2—2 in Figs. 1 and 3, and

Fig. 3 is a transverse sectional elevation, taken along the line 3—3 in Fig. 2.

Referring to the drawings, I have shown for illustration a stoker of the side retort type, comprising a hopper 10 and a fuel feeding plunger or ram 11 by which fuel is

forced through a casing or chute 12 in the front wall 13. The fuel is received in a side retort 14 from which it is transversely advanced by overfeed grates 15 to dumping plates 16 adjacent the side wall 17.

The coal feeding ram or plunger 11 is actuated by a crank shaft 18 connected by suitable gearing with a driving shaft 19. The parts thus far described are shown for illustration only, and in themselves form no part of my present invention. For a more complete description of the construction and operation thereof and particularly of the connections between the shaft 19 and the crank shaft 18, reference is made to my co-pending application Serial No. 556,012, filed April 22, 1922.

An air chamber 20 is formed beneath the retort 14 and a casing or sleeve 21 extends through the front wall 13 and provides for admission of air thereto. The air from the chamber 20 is conducted to the several parts of the stoker as may be required.

In the form shown in the drawings, a portion of the air is delivered through tuyère openings 22 in the side wall 23 of the retort, the air pressure for these openings being controlled by a damper 24. Additional air is supplied through tuyère openings 25 in the opposite wall of the retort and a second air chamber 26 receives air from the chamber 20 for the overfeed grates 15, the pressure of this air being controlled by a damper 27.

A fan 30 is mounted in the casing 21 and is shown in the drawings as directly connected to a turbine 31 by which it is driven. This turbine may be operated by air or steam supplied through a pipe 32 or in any other convenient manner.

A shaft 33 extends forward from the turbine and is provided with a worm 34 engaging a worm wheel 35 on the driving shaft 19. The turbine 31 is thus adapted to drive the fan 30 directly and to actuate the fuel feeding ram 11 through speed-reducing connections by which the proper ratio of movements is maintained. Any other suitable speed-reducing connections may be substituted for that herein shown.

The driving mechanism for the stoker is thus disposed within a very limited space at the front of the stoker where it is conveniently accessible for inspection or repair and

a single actuator only is required to operate the entire stoker and to supply the necessary air under pressure therefor.

Having thus described my invention, it should be understood that the mechanism shown herein is illustrative only, as I do not wish to be limited to the specific details herein disclosed otherwise than as set forth in the claim, but what I claim is:—

- 10 An underfeed stoker having, in combination, a front wall with air and fuel openings therein, a retort extending rearward from the front wall of said stoker, a ram to feed coal through the fuel opening in said wall to said retort, a crank shaft, connections between said crank shaft and said ram for
- 15

driving the ram, a motor mounted forward of the air opening in the wall, a shaft for said motor, the rear end of said shaft extending into said air opening, a fan driven 20 by said motor, mounted on said end of the shaft, in said opening, the motor shaft also extending forwardly of the motor, a speed reducing connection between said forwardly extending motor shaft and said crank shaft, 25 said connections including a worm and worm wheel and providing a slow powerful feeding movement of the crank shaft and ram.

In testimony whereof I have hereunto 30 affixed my signature.

ROBERT SANFORD RILEY.
